UNITED STATES PATENT OFFICE.

AMORY J. HOLDEN, OF OAKHAM, MASSACHUSETTS.

FURNACE.

SPECIFICATION forming part of Letters Patent No. 365,071, dated June 21, 1887.

Application filed February 5, 1887. Serial No. 226,678. (No model.)

To all whom it may concern:

Be it known that I, AMORY J. HOLDEN, a citizen of the United States, residing at Oakham, in the county of Worcester and State of Massachusetts, have invented certain new and useful Improvements in Heating-Furnaces, of which the following is a specification, reference being had therein to the accompanying drawings.

10 The object of my invention is to provide a heating-furnace (more particularly adapted for burning wood as fuel) which may be constructed at a comparatively small cost, and by which the largest possible amount of heat for 15 warming a building can be obtained from a given amount of fuel.

In the accompanying drawings, Figure 1 is a side view, with the housing or inclosing-jacket partly broken away, of my improved 20 furnace; and Fig. 2 is a front end view of the same.

A denotes the fire drum or cylinder, and B the radiating cylinder placed above the fire-drum, these cylinders being connected at their 25 rear ends by a smoke-pipe, C, and the radiating drum opening at its forward end into the smoke-stack D. The drums A and B are of sheet metal, (which will vary in thickness according to the size of the apparatus,) and are 30 provided at their front ends with cast-iron rims a b, secured to flanges on the drums by bolts c, the said rims securing the heads of the drums with almost air-tight joints, and the rear ends of the drums may be similarly 35 constructed, if desired.

The fire-drum A is provided at its front end with a door, E, which is opened to introduce the fuel, and with a sliding or other similar damper, F, and the radiating drum is provided 40 at its forward end with a check-draft door, G, which may be opened more or less, when desired.

The heating-drums are inclosed within a housing or jacket, H, which will preferably be 45 of brick, as shown, unless it is desired to heat the cellar or basement where the furnace is located, in which case the said jacket may be of galvanized sheet-iron, the said housing or jacket forming the heating-chamber I outside 50 of the drums. The housing H has suitable openings, J, at its bottom for the admission of the cool air, said openings being made to com-

municate with the open air in any suitable or well-known manner, if desired. The said housing is also preferably provided at its rear end with a door, K, (indicated by dotted lines in Fig. 1,) which may be opened to give access to the drums, and the latter may also be inspected through the doors E and G at their front ends.

To give the air to be heated a circuitous course as it rises, so as to enable it to absorb a large amount of heat from the drums without requiring the latter to be overheated, I provide the heating-chamber I with air-diverting plates or partitions L L' L², which may be let into the brick-work of the housing or jacket H, as shown, and which may also be attached by small brackets d to the drums. The plates or partitions L extend from the fire-drum A to the side walls of the housing H, and from the rear end of the heating-chamber I nearly to the forward end thereof, and the plates L² are similarly arranged relative to the radiating drum B. The plate or partition L' extends 75 entirely across the heating-chamber between the drums A and B, and from the forward end of the said chamber rearward nearly to the connection smoke-pipe C at the rear ends of the said drums. Thus the rising air to be 80 heated will be caused to pass to the forward end of the heating-chamber, then to the rearward end thereof, and then again to the forward end before it finally passes upward into the hot-air pipes M at the top of the housing 85 H. The bricks forming the top of the said housing are shown in the drawings as being supported by iron bars e, extending from one side wall of the housing to the other.

With my furnace constructed in the manner above described a very large proportion of the heat of the fuel passes through the sheet-metal drums, and is absorbed by the circuitously-moving air passing upward through the heating-chamber, so that the said drums 90 need never be heated red hot, and they will therefore last a long time without being burned out. Moreover, the brick housing or jacket H will absorb a large quantity of heat when fresh fuel has been supplied to the fire-drum 95 and the fire is the hottest, and this heat will again be given out when the fire gets low, so that the heat supplied to the building will be more or less regulated by the brick-work sur-

rounding the heating-chamber, and thus the heat supplied from the wood fire (for which my furnace is more particularly intended) will approximate in steadiness the heat from a coal-burning furnace. If, from any reason, it becomes necessary to remove the fire and radiating drums from their housing, this can be readily done by removing a small portion of the front brick-work.

10 From the foregoing it will be apparent that the large amount of heat-radiating surface afforded by my drums and the circuitous course which the air must necessarily follow in passing through the heating-chamber, as well as 15 from the comparatively thin material of which the drums are composed, enables my furnace to combine a great heating capacity with economy of fuel, while the cost of construction thereof is comparatively small, all of which 20 has been demonstrated practically.

I do not wish to be understood as claiming, broadly, a heating-furnace comprising radiating and heating drums, or a heating-furnace having fire and heat radiating drums or chambers inclosed within a brick-work housing or jacket, or a series of air retarding or diverting plates or diaphragms within a heating-chamber, my invention consisting in the particular arrangements and combination of parts here- 25 30 inafter indicated by my claims.

Having thus described my invention, I claim and desire to secure by Letters Patent—

1. The combination, with the fire-drum A and the radiating drum B, above the said fire-

drum and connected therewith at its rear end, 35 of the enveloping housing or jacket H, forming the heating-chamber I, the air-diverting plates or partitions L and L², extending from the rear end of said chamber nearly to the front end thereof, and from the drums A and B to the side walls of the said housing, and the air-diverting plate or partition L', extending entirely across said chamber and from the front end thereof nearly to the rear end of said drums, substantially as set forth. 40 45

2. The combination, with the sheet-metal fire-drum A, having the door E and the damper F, of the sheet-metal radiating drum B, above the said fire-drum and connected therewith at its rear end, the latter drum having at its forward end a smoke stack or pipe and a check draft-door, the enveloping brick-work housing or jacket H, forming the heating-chamber I, the air-diverting plates or partitions L and L², extending from the rear end of the said chamber nearly to the front end thereof, and from the drums A and B to the side walls of the said housing, and the air-diverting plate or partition L', extending entirely across the said chamber and from the front end thereof nearly to the rear ends of the 50 55 said drums, substantially as set forth.

In testimony whereof I affix my signature in presence of two witnesses.

AMORY J. HOLDEN.
